PAINT APPLYING APPARATUS

Filed June 1, 1949

UNITED STATES PATENT OFFICE

2,578,918

PAINT APPLYING APPARATUS

Leonard Boddy and Smith B. Atwood, Jr., Ann Arbor, Mich., assignors to King-Seeley Corporation, Ann Arbor, Mich., a corporation of Michigan.

Application June 1, 1949, Serial No. 96,548.

3 Claims. (Cl. 91—43)

1 This invention relates generally to devices for applying paint or the like and is particularly adapted among other uses for applying a fluorescent paint to indicating dials.

An object of this invention is to provide such a device which will apply paint in controlled quantities and in controlled spaces.

Another object of this invention is to provide such a device whereby fluorescent paint may be applied to preformed cavities.

Another object of this device is to provide means for maintaining the paint thoroughly mixed.

Another object of this device is to provide means for controlling the pressure at which the paint is supplied to the discharge nozzle.

A further object of this invention is to provide such a device whereby a plurality of similar cavities may be filled at any one time.

Other objects of this invention will be apparent from the specification, the appended claims and the drawings in which drawings:

Figure 1 illustrates a paint-applying device embodying the invention;

Fig. 2 is a detailed view of the nozzle of Fig. 1 taken substantially along the line 2—2 of Fig. 1;

Fig. 3 is a view taken substantially along the line 3—3 of Fig. 2;

Fig. 4 is a view taken substantially along the line 4—4 of Fig. 1;

Fig. 5 is a view taken substantially along the line 5—5 of Fig. 4;

Fig. 6 is a modified form of the invention showing a plurality of modified nozzles arranged for tandem operation as by a pantograph; and

Fig. 7 is a view taken substantially along the line 7—7 of Fig. 6 showing a detailed view of the modified form of nozzles shown in Fig. 6.

Generically, the invention contemplates a new device for applying a fluorescent paint to numerals indented in transparent plastic indicating dials, such as those of an automobile speedometer. The paint to be applied is stored in a suitable container 1 and maintained agitated by means of a rotatable stirrer 6. Paint from the container 1 flows through a flexible conduit 16 such as a rubber tube to an applying nozzle 20. The nozzle 20 is of suitable size to be conveniently held in a person's hand and guided about the numerals to flow paint into the recessed numeral. The discharge of paint from the nozzle 20 is controlled by means of the lever 28. Preferably the container is carried on a suitable support at an elevation above that upon which the dial 5 rests whereby the liquid head

of the paint causes the paint to flow outwardly of the discharge nozzle.

More specifically, the container 1, which may be substantially in the shape of an inverted necked bottle, has an open top which is closed by means of a housing 2 containing a fluid motor. Pressure fluid is supplied to the inlet 3 of the motor as by a conduit 4 connected to a suitable source. Fluid rather than electric motors is preferred to reduce fire hazards from the flammable solvents usually used. The stirrer or agitator 6 may be directly carried by the rotatable shaft of the motor and extends downwardly into the container 1. The container 1 is preferably carried on a mounting 8 which is adjustably supported by a vertical support 10 and held in a selected position by the set screw 12. The lower necked end of the container 1 provides a discharge opening 14 and receives the upper end of the flexible tube 16. The lower end of the tube 16 is connected to the inlet conduit 18 of the discharge head or nozzle 20.

The nozzle 20 is provided with a fluid flow passageway 22 extending longitudinally therethrough and is in open fluid flow communication with the interior of the tubing 16. Flow through the passageway 22 is controlled by means of gate valve 24 which has an actuating portion 26 extending outwardly of the nozzle 20 and which is operatively connected with one end portion of the control lever 28. The control lever 28 is pivotally secured to the nozzle 20 as by means of pin 30 carried by the nozzle 20. A helical coil compression spring 32, under compression 35 between the control lever 28 and the wall of the nozzle 20, acts to hold the control lever 28 in a clockwise rotated position whereby the gauge valve 24 is in a position to block flow of paint through the passageway 22.

Upon squeezing the lower end of the control lever 28, the spring 32 will be compressed and the gate valve 24 will open to permit flow of paint through the passageway 22. An orifice member 34, in fluid flow communication with the lower end of the passageway 22, is carried by the nozzle 20 and has a discharge orifice 36 for discharging the paint into the recessed figures 38 of the transparent plastic dial plate 5. Upon release of the control lever 28 by the operator, the spring 32 acts to rotate the lever 28 in a clockwise direction moving the gate valve 24 into blocking position with respect to the passageway 22.

In Fig. 7 there is shown a modified form of the nozzle 20A which comprises a hollow cylin-

drical member 50 externally threaded at its lower end to receive the nozzle member 52 having an orificelike outlet 54. The upper end of the nozzle 50 screw-threadedly receives a solenoid 56 having a movable core 58. A rodlike valve member 60 is secured at its upper end to the core 58 and extends downwardly through the member 50 and, when the solenoid 56 is de-energized, into the outlet orifice 54. A packing member 62 is provided above the paint inlet 64 to the member 50.

Upon energization of the solenoid 56 the armature 58 is pulled upwardly moving the valve member 60 upwardly and outwardly of the outlet orifice 54 to permit paint to flow from the tubing 60 through the member 50 and the orifice 54 into a numeral 38.

As shown in Fig. 6, a plurality of these nozzles 20A may be connected together in pantograph arrangement whereby a plurality of the dials 5 may be done at any one time. In this instance all of the solenoids 56 of the nozzles 20A are connected together in parallel circuit to a suitable source of electric current energy supply L1 and L2 through a suitable switch 66 which may be foot-actuated or if desired may be hand-actuated as by a lever 28 carried on the one of the nozzles 20A which is operated by the operator.

The nozzle 20 or nozzle 20A is grasped by the operator and the outlet 36 or 54 thereof is inserted within the recess forming the numeral 38 after which the actuator 28 is pressed or the solenoid 56 is energized to permit paint to flow into the recess numeral 38. It will be obvious for best flowing of the paint, the nozzle 20 or 20A will be directed as in a tracing operation in the recess figures 38. If desired air pressure may be applied above the level of paint in the container 1 as by means of the tubing 70 or if desired the fluid head of the paint may be used and the tubing 70 opened to atmospheric pressure. If it is desired to stir the paint within the tubing 16 an elongated wirelike member 72 may be secured to the lower end of the stirrer 6. Such member 72 extends down within the tube 16 so that as the stirrer 6 rotates, the wire 72 will also be rotated thereby mixing the paint within the tubing 16.

What is claimed and is desired to be secured by United States Letters Patent is as follows:

1. An apparatus for applying paint comprising a paint storage container having an open top and a closed lower end wall with an outlet aperture extending through said end wall, an elongated

distributing member having a passageway extending longitudinally therethrough, a flexible tube interconnecting said outlet and said passageway, a flow controlling member carried by said member and movable to control flow of fluid through said passageway, an operating means for said flow controlling member carried by said distributing member, a cap member for said container and closing said open top, agitating means carried by said cap and comprising a spiraled ribbon extending into said container, and a fluid motor carried by said cap and operatively connected to actuate said agitating means.

2. In an apparatus of the character described, a container for the storage of liquid medium and having an outlet, a distributing head having an outlet, a flexible conduit connecting said container outlet with said head, valve means in said head controlling flow of said liquid medium outwardly of said head outlet, a rotating member positioned in said container for agitating said liquid medium and held against longitudinal movement therein, an elongated flexible member extending from said container into said flexible conduit and operatively connected to said rotating member for rotation thereby, and a prime mover carried by said container and operatively connected to said rotating member for rotating said rotating member and said flexible member.

3. The combination of claim 1 in which said container outlet aperture is in axial alignment with the axis of rotation of said ribbon, and in which an elongated flexible member extends through a major portion of said flexible tube and is operatively connected for rotation by said motor whereby the fluid within said flexible tube is agitated.
